[57] ABSTRACT

A Rankine cycle rotary engine and gas flow control valve mechanism used therewith. A housing of the engine forms a pair of cylindrical cavities in which primary and secondary rotors are mounted for rotation about spaced, parallel axes. Three outwardly projecting lobes on the primary rotor intermesh with three concaval recesses on the secondary rotor, and a timing gear train is provided to turn the secondary rotor in opposite and equal angular rotation with the primary rotor. Gas under pressure is directed through a distributor chamber to a flow control valve sleeve mounted for axial sliding movement concentrically within the primary rotor. Pairs of radially extending distributor passageways are formed in each of the lobes to direct gas from the valve into successive expansion chambers formed between the intermeshing lobes and recesses. The valve sleeve is formed with a pair of axially spaced apart flow control ports. The control ports are bounded by pairs of admission and cutoff edges which diverge apart in opposite axial directions. Means is provided to axially position the valve sleeve for throttling by varying the angular sector of the control port opening which is in register with the distributor passageways, and further to carry either port into register with these passageways for forward, braking or reverse engine operation. Residual gas from secondary rotor recesses which have disengaged from their associated primary rotor lobes is directed through secondary passages to expand and act against the primary rotor.

ROTARY ENGINE WITH INTERENGAGING ROTATING MEMBERS AND REVERSING VALVE

BACKGROUND OF THE INVENTION

This invention relates in general to rotary engines, and in particular relates to rotary engines which operate on a Rankine cycle. The invention also pertains to flow control valves used with such engines.

There has been an increasing recognition of the many inherent disadvantages and limitations of internal combustion engines, such as those operating on Otto or Diesel cycles, as well as the disadvantages and limitation of reciprocating engines which operate on either internal or external combustion cycling. A disadvantage of considerable importance in internal combustion engines is the inability to effectively reduce harmful exhaust from the engine, with the concomitant increase in air pollution. It is known that external combustion engines such as those operating on the Rankine cycle and using a working fluid such as steam can reduce or eliminate many of these disadvantages. Combustion may be more effectively controlled in a Rankine cycle system to insure more complete fuel burning, and without producing large amounts of harmful by-products such as carbon monoxide, unburned hydrocarbons and oxides of nitrogen.

It is also widely recognized that rotary engine designs, whether operating on Rankine or Otto cycle principles, provide important advantages over reciprocating engines. Generally rotary engines can be balanced to run at relatively high rotation speeds without the undesirable vibrations, high stresses and high inertia loads which otherwise occur from the rapid acceleration and deceleration of moving parts in a reciprocating engine.

Accordingly, the need has been recognized for an improved engine which achieves the many advantages and desirable features of both Rankine cycle operation and rotary engine design.

OBJECTS AND SUMMARY OF THE INVENTION

It is a general object of the invention to provide an improved rotary engine adapted for operating on a Rankine cycle to produce mechanical work from a source of gas under pressure (e.g. steam or the like).

Another object of the invention is to provide a rotary engine of the character described which achieves the many advantages of Rankine cycle operation such as reduced exhaust emission and more complete fuel burning through a structure having a relatively high power-to-weight ratio, a favorable torque curve, and with engine elements which undergo pure rotary motion that is productive of relatively smooth and vibration-free operation.

Another object is to provide a rotary engine of the character described which incorporates a relatively few number of moving parts, is relatively inexpensive in construction and operation, and is relatively simple to repair and maintain.

Another object is to provide a valve mechanism which controls gas flow to an engine of the character described in a manner affording selective forward, reverse, braking and throttling operation under influence of a single control element.

The foregoing and additional objects and features of the invention are provided in the invention by a rotary

5 engine having primary and secondary rotors mounted for rotation within a housing about parallel, spaced-apart axes. A plurality of lobes are formed on the primary rotor for meshing engagement with corresponding recesses formed on the secondary rotor. A gas under pressure developed from an external combustion process in a Rankine cycle system is directed by flow control means into expansion chambers which are successively formed between the intermeshing lobes and recesses. The resultant of forces from the gasses within the expansion chambers are balanced on the secondary rotor, but produce a torque force acting eccentrically on the primary rotor. This torque force turns the primary rotor about its axis to produce mechanical work and at the same time drives a timing gear train for turning the secondary rotor in equal and opposite angular rotation with the primary rotor. The flow control means includes a valve sleeve adapted to control both forward and reverse engine rotation, braking, and engine throttling by the single function of axial adjustment of the sleeve. The valve sleeve includes forward and reverse ports formed at axially spaced positions with oppositely diverging admission and cut-off edges arranged so that varied axial positions of the sleeve moves variable angular sectors of port openings into register with paired distributor passageways leading through the lobes and opening into the expansion chambers. Provision is made for balancing the pressure forces acting on the valve sleeve so that the force required for axial shifting of the sleeve is relatively small. Secondary passageways are formed in the housing to direct residual gases from the recesses which have disengaged from their associated lobes so as to act upon and develop additional torque against the primary rotor.

BRIEF DESCRIPTION OF THE DRAWINGS

FIG. 1 is a transverse cross sectional view of a rotary engine in accordance with the invention and illustrating the primary and secondary rotors in one operative position;

FIG. 2 is a view similar to FIG. 1 illustrating the primary and secondary rotors in a second operative position;

FIG. 3 is an axial cross sectional view taken along the line 3-3 of FIG. 1; and

FIG. 4 is an elevational view of a component control valve member for the engine of FIG. 1.

DESCRIPTION OF THE PREFERRED EMBODIMENTS

Referring to the drawings FIG. 1 illustrates generally at 10 a preferred embodiment of the rotary engine of the present invention. The rotary engine 10 is specially adapted for use in a Rankine cycle system where a working fluid (e.g. steam or a Freon gas) is generated by means of the combustion of a fuel in an external combustion chamber connected in either open or closed fluid flow circuitry. In a closed circuit arrangement suitable condensers, pumps, boilers, piping and other equipment, not shown, would be employed for condensing and recovery of the expanded gases exhausting from the engine 10. Such equipment is broadly conventional and is not shown herein as it forms no part of the present invention.

Rotary engines 10 includes a housing 11 comprising housing half sections 12, 13 bolted together about their

outer periphery by suitable means such as the circle of bolts 14. The bases of the two housing sections define a flanged support 15 adapted for anchoring by suitable means such as bolts to a foundation or engine support. The interior volume between the two housing sections defines an upper cylindrical walled cavity 16 and a lower cylindrical walled cavity 17 overlapping with and of a greater diameter than the upper cavity.

A primary rotor 18 is mounted within lower cavity 17 for rotation about a first axis 19 extending longitudinally of the engine. A plurality, preferably three, of radially outwardly extending lobes 21, 22 and 23 are formed on the primary rotor at equally spaced apart circumferential positions. The outer peripheral surface of each lobe defines a section of a cylindrical surface adapted to move in close-fitting, sealing relationship with the inner surface of lower cavity 17. The axial end faces of the primary rotor are in close-fitting rotary sealing contact with the opposing housing faces forming the lower cavity. As best illustrated in FIG. 3 annular cylindrical supports 24, 25 extend axially from either end of the primary rotor, and these supports are journaled for rotation within sleeve bearings 27, 28. The right-hand sleeve bearing 27 is carried within a cylindrical support 29 formed integrally with and extending outwardly from housing section 12, and the opposite sleeve bearing 28 is carried within a cylindrical support 30 formed integrally with and extending outwardly from an end cover 32 secured to housing section 13 by suitable means such as the circle of machine screws 33. The primary rotor 18 is connected to the desired end use application or power shaft, not shown, by suitable means such as the drive gear 34 keyed to an output shaft 36 which is formed integrally with a circular end plate 37 mounted at the end of support 25.

The interior volume which lies concentrically within the primary rotor forms a gas distributor chamber 38. Gas is directed to this distributor chamber from a suitable supply conduit, not shown, connected at one end with the source of gas under pressure (e.g. a steam generator or boiler) and connected at its other end with flanged inlet port 39 which feeds gas into an annular channel 41 formed in sleeve bearing 27. A plurality of radially extending circumferentially spaced openings 42 are formed through the end support 24 of the primary rotor, and these openings turn with the rotor in register with annular channel 41 to direct inlet gas into the distributor chamber. A circular end plate 43 is secured within a recessed seat of end support 24 to define the outer end wall of the distributor chamber.

A secondary rotor 44 is mounted within upper cavity 16 on a shaft 46 for rotation about an axis 47 parallel with and spaced vertically above the primary rotor axis 19. A plurality of radially inwardly projecting concaval lunettes or recesses 48, 49, 50, equal in number to the number of primary rotor lobes, are formed in the secondary rotor. The outer peripheral surfaces or rim portions 52 of the secondary rotor which lies between the recesses are sized for close-fitting rotary movement within cavity 16 to provide a fluid seal for the gasses within the working or expansion chambers 53 which are successively formed between the intermeshing lobes and recesses. The axial end faces of the secondary rotor are in close-fitting rotary sealing contact with the opposing housing faces forming the upper cavity. Shaft 46 for the secondary rotor is rotatably journaled at one end by sleeve bearing 54 within a boss 55

formed integrally with housing section 12, and is rotatably journaled at its other end by sleeve bearing 54 within a boss 56 formed integrally with end cover 32.

Timing means is provided for turning secondary rotor 44 in one-to-one synchronous driving relationship with primary rotor 18. This timing means preferably comprises a gear train including a drive gear 57 mounted about and keyed for rotation with the cylindrical support 25 of the primary rotor. A driven gear 58 is provided with the same number of teeth as the drive gear, and the driven gear is keyed for rotation with secondary rotor shaft 46. The two gears 57, 58 intermesh to turn the secondary rotor in equal and opposite angular relationship with the primary rotor for maintaining intermeshing engagement of the respective lobes and recesses.

The configuration of the primary and secondary rotors together with their respective cylindrical cavities 20 are symmetrical so that the engine is adaptable for forward and reverse rotational operation. The peripheral surface of the primary rotor lobes and secondary rotor recesses define substantially gear tooth profiles so that the opposed surface portions of intermeshing lobes and recesses are in close-spaced contact for sealing the gases within the expansion chambers. The primary and secondary rotors and their respective axes are sized and spaced apart with predetermined dimensions so that, with the two rotors in their dead-center positions as illustrated in FIG. 1, the expansion chamber 53 defines a crescent configuration in section between the outer surface of the lobe 21 and the opposed root portion of the associated secondary rotor recess 49. This expansion chamber has an axial width equal to the axial width 25 of the two rotors. With the rotors turned away from the dead-center position, e.g. to the position illustrated in FIG. 2, the resultant force from pressurized gas from within the expansion chamber acts eccentrically to and imparts a driving torque against the primary rotor. It 30 will be noted that, with the lobes and recesses in engagement, the pressure forces within the expansion chamber act against projected areas of the secondary rotor which are equal on either side of its axis of rotation so that there is no net driving torque imparted to the secondary rotor. Suitable means may be provided to drive the primary rotary past its dead-center position should it stop in this position. For example, one or more pairs of additional primary and secondary rotors 35 may be drivingly connected out of phase with the illustrated rotors, or a starting motor and flywheel arrangement, not shown, may be coupled with output shaft 36.

Means for controlling the flow of pressurized gas into the successive expansion chambers is provided. This flow control means includes pairs of substantially radially extending distributor passageways 59, 60 formed in each of the three lobes 21-23. The passageways for each lobe diverge outwardly from a common inlet port 62 into distributor chamber 38, with the passageways leading to outlet ports 63, 64 opening through the outer peripheral surface of respective lobes for communication with the expansion chambers 53. The outlet ports are circumferentially spaced-apart to extend delayed cutoff to gas flow into each expansion chamber, such as where it is desired to develop full engine power. That is, movement of each primary rotor lobe out of meshing engagement with its associated recess carries the lead-

ing outlet port, depending on the direction of rotation, across the face of cylindrical cavity 17, thus blocking flow through the lead passageway. With the present invention the trailing outlet port is positioned so that it remains in communication with the expansion chamber for extended gas feed throughout a further arc of rotation until the primary rotor carries this outlet port across the face of the cavity 17.

The flow control means further includes a cylindrical valve member 66 comprising a hollow cylindrical shell or sleeve mounted both for axial sliding and rotary movement relative to the inner wall of distributor chamber 38. A pair of axially spaced end walls 67, 68 are carried at opposite ends of the valve sleeve. A control shaft 69 mounted on end wall 67 projects outwardly in slidable and rotatable sealing relationship through a central opening 71 formed in rotor end plate 43, and a support shaft 72 mounted on the opposite end wall 68 projects outwardly in slidable and rotatable sealing relationship through a central opening 73 formed in output shaft 36. A control lever 74 or a hinged foot pedal, not shown, is connected for operating the control shaft for axially sliding movement within the distributor chamber. Suitable means such as the shaft end pin 76 and slotted frame 77, or straight sliding splines, not shown, is provided for restraining the valve sleeve from rotation with respect to housing 11. A plurality of openings 80 are formed in the two sleeve end walls 67, 68 for communicating gas received from inlet port 39 both into the interior volume of the valve sleeve and into the volume between end wall 68 and the opposed end plate 37 of the primary rotor. The pressure of gas is thus evenly distributed on opposite ends of the valve sleeve so that the resultant thrust force acting on the valve sleeve is minimal. This permits the valve sleeve to be shifted axially in either direction with a relatively small operating force.

Valve sleeve 66 is formed with a pair of flow control ports 78, 79 specially adapted to control forward, reverse, braking and throttling engine functions by means of only one control input, that is through selection of the axial position for the valve sleeve. The two ports are defined by openings through the cylindrical wall of the sleeve at axially spaced-apart positions. The peripheral boundaries of the openings include admission edges 81, 82 (FIG. 4) extending parallel to the primary rotor axis together with cutoff edges 83, 84 which diverge apart in opposite directions from the admission edges. The remaining sides of the openings are defined by circular edges 86, 87 extending from the outer end of the cutoff edges perpendicular to the outer end of respective admission edges. With the valve sleeve developed into an imaginary plane, the boundaries of the two control ports would substantially define right triangles, although the cutoff edges could be curvilinear, as desired. Because the valve sleeve does not turn relative to the housing, the two admission edges for the control ports are fixed in position with respect to a vertical plane passing longitudinally through the two axes about which the rotors turn. This configuration initiates the admission of gas into the expansion chambers as the primary rotor turns through its successive dead-center positions for the three lobes. This uncovers distributor inlet ports 62 as they move into register with the admission edge of either the forward or reverse port, irrespective of the axial throttling position of the valve sleeve. With the control shaft shifted to the position il-

lustrated in FIG. 3 at which valve sleeve is in its extreme left-hand position, it will be seen that, with a clockwise rotation of the primary rotor as viewed in FIG. 1, successive distributor passage inlet ports remain in fluid communication with the gas distributor chamber throughout a maximum angular sector of rotation until the inlet ports move over and are occluded by cutoff edge 83. Because this cutoff edge diverges from admission edge 82 in an axial direction, the arc of primary rotor rotation through which the distributor inlet ports remain in communication is a function of the axial position of the valve sleeve. Gas flow throttling for power control thereby is varied between engine shutdown, at which the valve sleeve is shifted to a position substantially axially centered within the rotor, and the full power position of FIG. 3.

With valve sleeve shifted to an opposite position at the right-hand end of the distributor chamber, as viewed in FIG. 3, braking and reverse port 79 is carried so that it is in register with the successive distributor inlet ports. The admission edge 81 of port 79 is positioned in fixed relationship with respect to the housing so that with primary rotor moving counterclockwise, as viewed in FIG. 1, successive distributor inlet ports 59, 60 are uncovered as they move across the primary rotor dead-center position. These inlet ports remain in fluid communication with distributor chamber 38 to direct pressurized gas into successive expansion chambers 53 up to the point at which they are occluded by cutoff edge 84. Again, gas flow throttling is controlled as a function of axial position of the valve sleeve in that the inlet port exposure is a function of the angular sector of travel of the distributor passage inlet ports between the admission and cutoff edges.

Means is formed in housing 11 to utilize the energy of secondary expansion of the gas which remains in successive recesses 48 - 50 following disengagement from the lobes. This means includes secondary passages 88, 89 formed on either side of the housing. The passage 88 extends from an inlet port 91 opening through the side wall of secondary rotor cavity 16 to an outlet port 92 opening through the side wall of primary rotor cavity 17. The opposite secondary passage 89 similarly includes an inlet port 93 opening into the opposite side wall of secondary rotor cavity 16 and an outlet port 94 opening through the opposite side wall of primary rotor cavity 17. Assuming forward engine operation, or counterclockwise rotation of the secondary rotor as illustrated in FIG. 2, the residual gas contained within the recess 49 which has just disengaged from lobe 21 continues to expand and act against primary rotor 18 up to the point that secondary rotor edge 96 moves across housing edge 97. Following this the residual gas from the recess expands into secondary passage 89. As outlet port 94 of this passage is uncovered by the trailing edge 98 of lobe 21 the contained gas discharges into cavity 17 where it acts against the primary rotor. Similarly, in reverse engine operation, with the secondary rotor turning clockwise as viewed in FIG. 2, the residual gas contained within successive recesses flows through secondary passage 88 and into the opposite side of cavity 17 to act against the primary rotor. This secondary expansion of the residual gasses acts to increase the power and efficiency of the rotary engine.

Exhaust means is provided to expel the expanded gasses from the cavity of the primary rotor. This means

includes an exhaust chamber 99 formed at the lower end of housing 11 with lateral sides 101, 102 diverging upwardly to the side walls of cavity 17. An exhaust port 103 expels gasses outwardly from the exhaust chamber, with the engine running in either forward or reverse directions, as the trailing edges of the primary rotor lobes move across and uncover the edges 120, 105 of the exhaust chamber side walls. The exhaust port either expels the gases directly to ambient, or through piping, not shown, leading to a suitable condenser, as where the rotary engine is operated in a closed circuit system.

In operation, it will be assumed that rotary engine 10 is employed in a closed circuit system for operation as a Rankine cycle engine. The working fluid employed is steam supplied from a suitable boiler into inlet port 39 at a temperature of approximately 850°F. and a pressure of approximately 800 psi. For forward engine operation, i.e., clockwise rotation of primary rotor 18 as viewed in FIG. 1, control shaft 69 is axially shifted by the control linkage 74 to a position at which the apex between admission edge 82 and cutoff edge 83 of port 78 registers with the path of movement of the inlet ports 62 for the distributor passageways. Where the primary and secondary rotors are in dead-center position, i.e., with any one of the primary rotor lobes in an exact twelve o'clock position, initial clockwise motion is imparted to the primary rotor either through a second pair of primary and secondary rotors, or through a suitable starting motor coupled to output shaft 36. Steam from inlet port 39 initially flows through distributor chamber 38 into the interior of valve sleeve 66. The steam then flows both through the opposite sleeve end wall openings 80 for pressure balancing of the sleeve, and through forward control port 78 and the distributor passageway inlet ports 62 of the first lobe 21. The steam discharges from the two distributor passageways into the expansion chamber 53 defined between the outer peripheral surface of the lobe and the opposing root surface of recess 49. With lobe displaced through an arc of travel past its dead-center position the resultant pressure forces within the expansion chamber act against the primary rotor eccentric to its axis of rotation, thereby imparting a driving torque to the rotor and output shaft 36. At the same time, the resultant pressure forces within the expansion chamber act directly through the axis of rotation of secondary rotor 44 irrespective of its angular position so that no driving torque is imparted to the secondary rotor.

Rotation of the primary rotor turns drive gear 57 and driven gear 58 to rotate secondary rotor 44 in one-to-one ratio and in opposite rotational direction to synchronize the meshing engagement of the lobes and recesses. Sealing of the expansion chambers 53 is initially maintained between the lobe outer surfaces and the opposing surfaces of the recess, together with the sealing maintained between opposite end faces of the two rotors and the facing housing side walls. As the leading lobe edge 104 reaches the housing edge 97 sealing of the expansion chamber is maintained between the outer surface of lobe 21 and the opposing surface of the wall of cavity 17, and between the outer surface 106 of secondary rotor 44 and the opposing side wall of cavity 16. The trailing portion of the expansion chamber is sealed by the interface between the facing surfaces of the lobe and recess up to the point of lobe disengagement, after which sealing is maintained by the rolling

line of contact between the outer surface 107 of the secondary rotor and the inner cylindrical sealing surface 108 of the primary rotor, as best illustrated in FIG. 2.

Steam continues to be fed into the expansion chamber from the two distributor passageways 59, 60 until the lobe 21 rotates to a position at which the outlet port 63 of lead passageway 60 moves across and is occluded by housing edge 97. Because the trailing passageway 59 is circumferentially spaced behind the lead passageway the expansion chamber continues to be supplied with steam until the trailing outlet port 64 moves across and is occluded by housing edge 97. The provision of the pair of leading and trailing distributor passageways makes it feasible to delay cutoff of steam flow for additional power and increased efficiency, and this is of special importance where the sleeve valve is shifted towards its full power position.

As illustrated in FIG. 2 the expansion chamber 53 enlarges in volume as the two rotors turn such that the total volume is a combination of the volume of recess 49 and the volume within cavity 17 which is swept behind lobe 21. When the trailing edge 98 of this lobe moves across and uncovers the outlet port 94 of secondary passage 89, the residual volume of steam from recess 49 discharges into cavity 17 behind the lobe to act against the primary rotor. This secondary expansion permits the utilization of the steam which would otherwise be trapped within the recesses as the recess trailing edges move across the housing edge 97.

To apply increased power to the engine, control shaft 69 is displaced to the left to carry valve sleeve to a position at which a greater angular sector between control port admission edge 82 and cutoff edge 83 is brought into register with distributor inlet ports 62. The result is that the distributor inlet ports are in fluid communication with the steam within distributor chamber 38 for a greater circular arc of rotation such that a greater volume of steam is fed into the expansion chambers. At the extreme left hand position of the valve sleeve, as shown in FIG. 3, a maximum angular sector of control port registry is established so that full power is developed. As engine speed increases valve sleeve may be rotated about its longitudinal axis by suitable speed responsive governor control means, not shown, connected with shaft 69 so that the admission edge 82 is displaced counterclockwise, as viewed in FIG. 1, through a small arc of travel, thereby advancing the rate of steam supply into the expansion chambers for increased efficiency at high speeds.

Expanded steam from the expansion chambers is expelled through exhaust port 103 as the trailing edges 98 of successive lobes move across and separate from the edge between cavity 17 and the wall of exhaust chamber 99. Steam from the exhaust port is either expelled to ambient in an open circuit system, or is directed through piping into the condenser of a closed cycle system.

Where it is desired to brake the forward running engine valve sleeve 66 is shifted to the right, as viewed in FIG. 3, so that steam supply into the expansion chambers is progressively decreased and then terminated as the annular surface between the two ports 78, 79 registers with the distributor inlet ports. Further axial shifting of the valve sleeve in the same direction carries the apex of braking and reverse port 79 into register with the distributor ports. This causes steam to be fed into

the contracting volume defined between the successive recesses and lobes which are moving into meshing engagement. The pressure of the steam within this volume acts against and exerts a torque on the primary rotor opposite to the direction of rotation. The volume of steam which is admitted for braking, and therefore the magnitude of braking power, is a function of the angular sector between the admission and cutoff edges which registers with the distributor inlet ports, which in turn is dependent on the axial position of sleeve 66.

For reverse engine operation, valve sleeve 66 is axially shifted to the position which carries the desired angular sector of port 79 into register with the distributor inlet ports. Operation of the engine in reverse direction is similar to that explained above for forward engine rotation, with the movement of the two rotors being in opposite directional senses. In addition, the expansion of residual steam from the recesses 48-50 is through the secondary passage 88 which directs the steam into primary rotor cavity 17 on the opposite side of housing 11.

From the foregoing it is apparent that applicants have provided herein a new and improved rotary engine and gas flow control valve specially adapted for operation in a Rankine cycle engine. The invention provides the inherent advantages of both Rankine cycle operation and purely rotary motion for the engine elements. Operation of the engine through a Rankine cycle utilizing a working fluid such as steam or Freon vapor is productive of a continuously rising torque curve such that the engine will not stall-out under heavy load, nor does it have to be unloaded for restarting. As a consequence the need for a complex and costly transmission is obviated, and furthermore the engine is adapted for running under high loads at relatively low rpm. The Rankine cycle operation of the engine further is productive of relatively clean exhaust in that combustion is readily controlled in an external combustion chamber with the amount of harmful combustion by-products reduced or eliminated, and in addition relatively low-octane fuels may be efficiently burned. The elements of the rotary engine undergo purely rotary movement so that the relatively high inertia loading and high stresses associated with reciprocating engines is obviated, with the result that the engine runs smoothly, quietly and relatively vibration free. There are only two primary moving parts so that the engine is relatively simple and inexpensive in design and operation, with concomitant ease of maintenance and repair. The working fluid used in the system may be steam or Freon vapor and the like. The use of a gas such as Freon vapor affords relatively high specific power as a result of the vapor's relatively high density, and this working fluid provides other advantages which include a relatively lower boiling temperature, a relatively low freezing point, lower cycle temperature and pressures, and inherent lubricating properties. The sleeve valve of the engine is adapted for controlling forward and reverse rotational directions, engine braking, and throttling by the control of only one function, that is through axial shifting of the valve element. The sleeve valve is inherently balanced so that only relatively small shift forces are required to control engine operation. Furthermore, the sleeve valve does not rotate with respect to the housing so that it is not stressed by inertial forces from reciprocating parts, as compared to slide, piston and poppet valve arrangements.

While the foregoing embodiment is at present considered to be preferred, it is understood that numerous variations and modifications may be made therein by those skilled in the art and it is intended to cover in the appended Claims all such variations and modifications as fall within the true spirit and scope of the invention.

We claim:

1. In a valve for controlling the flow of gas from a source of gas under pressure to an engine having a gas expansion phase in its operative cycle for producing mechanical work, the combination of means forming a cylindrical chamber having an inlet in fluid communication with said engine, means forming a distributor passageway in fluid communication with said engine, a cylindrical valve member mounted for axial sliding movement within said chamber, means forming at least one flow control port in said valve member, means mounting said distributor passageway means for rotation about said valve member responsive to cycling of said engine, said flow control port being bounded about its periphery by an axially extending admission edge and a cutoff edge, said cutoff edge diverging from said admission edge along the outer periphery of said valve member, means forming a second flow control port in said valve member axially spaced from said first mentioned port, said second port being bounded about its periphery by a second admission edge substantially axially aligned with said first mentioned admission edge together with a second cutoff edge diverging from said second admission edge in a direction opposite of said first mentioned cutoff edge whereby axial movement of said valve member selectively moves either of said flow control ports into register with said distributor passageway means for forward or reverse cycling of said engine, and means to selectively move said valve member in an axial direction within said chamber to vary the angular sector between said admission and cutoff edges which registers with said distributor passageway means during each engine cycle.

2. A rotary engine to produce mechanical work from a source of gas under pressure, including the combination of a housing, a primary rotor of a given diameter mounted for rotation within said housing about a first axis, a plurality of circumferentially spaced, radially outwardly projecting lobes being formed on said primary rotor, a second rotor of a diameter different than said given diameter mounted for rotation within said housing about a second axis parallel with and spaced from said first axis, a plurality of circumferentially spaced, radially inwardly projecting recesses being formed on said secondary rotor, said recesses being sized for meshing engagement with respective ones of said primary rotor lobes to define successive expansion chambers therewith, flow control means to direct gas from said gas source through said primary rotor and into successive expansion chambers whereby the resultant pressure force of the gas therein acts eccentrically upon said primary rotor to turn the same about said first axis, said flow control means including means forming a distributor chamber within said primary rotor radially inward of said lobes and in fluid communication with said source of gas under pressure, means forming a plurality of distributor passageways within said primary rotor and extending substantially radially outwardly through said lobes, each distributor passageway including an inlet port positioned to register in

communication with said distributor chamber and further including an outlet port positioned at the outer periphery of respective lobes to direct gas into said expansion chambers, said flow control means further including valve means to selectively control the volume of said gas flowing from said distributor chamber into said distributor passageways, said valve means comprising a cylindrical valve member mounted within said distributor chamber for relative rotational movement with respect to said primary rotor, means forming a pair of flow control ports at axial spaced positions on said valve member, each of said control ports being in fluid communication with said distributor chamber and being bounded about its periphery by at least one axially extending admission edge positioned to establish 15

communication from said distributor chamber to said distributor passageway inlet ports when successive secondary rotor recesses are in meshing engagement with respective primary rotor lobes, each of said ports further being bounded about their peripheries by cutoff edges which diverge from their associated admission edges in opposite directions whereby registry of said control ports with said distributor inlet ports is effective to direct said gas into successive expansion chambers for respective forward and reverse rotation of said primary rotor, and means to move said valve member axially along said first axis to selectively move said control ports into and out of register with the inlet ports of said distributor passageways.
